Application August 21, 1951, Serial No. 242,902

37 Claims. (Cl. 216—29)

1

This invention pertains to a labeling machine and method, and more particularly relates to a machine and method for applying adhesive labels from a perforated strip to lengths of conduit and the like. The adhesive is generally at present of the heat-sensitive type, but the machine may be adapted or adaptable to operate with other adhesive for the labels.

A particular application of our machine is in applying so-called underwriters labels to lengths of electrical tubing or conduit. Such tubing is generally in lengths of about ten feet, and generally has a nominal diameter from $\frac{1}{2}$ inch to 2 inches, although it will be understood that the apparatus of the present invention may be adapted for applying labels to tubular articles of other lengths and other diameters.

In certain prior proposals for the use of labels having heat-sensitive adhesive, the label has not been severed from the strip until after it has been heated and preliminarily attached to the article. Therefore, the severing is difficult, in that the labels tend to stick to the cut-off knife.

One proposal which has been advanced for solving these difficulties involves a machine for putting a label on the upper side of a length of conduit and then exerting impact or pressure on the label, from above, to stick it to the conduit. However, the operation is rather cumbersome and such a machine is subject to the difficulty that it must be intermittently operated, such as by a one-revolution clutch, or special, periodic electrical controls or the like. This slows down the operation of the machine. Furthermore, such a machine must of necessity have many of its operating parts above the level of the table or conveyor means along which the tubes or conduits are carried, a condition which is not conducive to safety or to a satisfactory mechanical structure, or to convenience in actual operation.

Our machine overcomes the above mentioned difficulties, and in addition possesses many advantages not found in prior devices.

According to our method as practiced in a presently preferred manner, labels are applied to lengths of conduit and the like from a perforated strip by placing the foremost label of the strip partially over a heat application table, herein conveniently called a griddle, and then momentarily halting the movement of the strip. For example, if, as has been required for one purpose, the label is $1\frac{1}{2}$ inches long, we have found that very good results are attained if the label is pushed at this stage about $\frac{1}{8}$ inch over the griddle.

2

While the label is momentarily halted in this position, the label is severed from the rest of the strip, at its relatively cool, trailing end, and then the severed label is pushed the rest of the way onto the griddle where its adhesive is plasticized by heat. At this time, a length of conduit is rolled across the griddle under pressure and the label adheres to the conduit. The label is severed when only partially over the hot griddle to permit the severing means to be thermally insulated, e. g. separated from the griddle by an air gap, so that the severing means will not become heated and stick to the label.

Briefly, in its presently preferred form, our machine comprises a heated surface or griddle, means for rolling lengths of conduit thereacross under pressure, and means operable in timed relationship with the conduit lengths for pushing the foremost label of the strip partially over the griddle, momentarily halting the strip at this position, severing the foremost label from the remainder of the strip while the latter is halted momentarily, and pushing the now-severed label the rest of the way over and onto the griddle.

25 The means for pushing the foremost label onto the griddle includes a continuously operable, reciprocable pawl having a finger or equivalent means which is adapted to engage a perforation, or a plurality of perforations, between the foremost label and the remainder of the strip. When the pawl thus engages the perforation, it pushes the foremost label partially over the griddle at which point a reciprocable cut-off knife rises and severs the foremost label from the remainder of the strip. As the cut-off knife recedes, the pawl resumes its forward motion, pushing the now-severed label the rest of the way over and onto the heated griddle, where the adhesive material 30 on the exposed upper face of the label is rendered tacky or plastic. After the severed label is fully positioned upon the griddle, a length of conduit is rolled thereacross under pressure, and the label is thus applied to the conduit.

45 The machine preferably further includes means whereby the perforation between the foremost label and the remainder of the strip is positioned in engageable relationship with the finger of the pawl only when a length of conduit is advancing toward the griddle. Such means may conveniently include a timing lever in the path of the advancing lengths and operable thereby, and a trigger responsive to the position of the timing lever for lowering the perforation into the path of

the finger of the reciprocable pawl only when the timing lever is actuated by a length of conduit.

A roll-down belt above the conduit level, i. e. the level at which the successive conduits are advanced, is used for rolling the conduit across the griddle under pressure, and may conveniently be made adjustable whereby the same machine can be used for labeling conduit of different diameters. It will be understood that the successive tubes or lengths of conduit can conveniently be carried sidewise, i. e. each moving at right angles to its length, on suitable horizontal conveyor means leading to and away from the machine, such as a pair of conveyor belts which run past the machine and from which the conduits are slightly elevated while being advanced by the roll-down belt.

A side guide may be provided to align the ends of the conduit lengths, for instance as they approach on the conveyor means, so that the label will be applied a uniform distance from the ends of such lengths.

The tubes are preferably separated from each other before being engaged by the roll-down belt by means of a bumped section or structure which is arranged in the path of the tubes as advanced by the conveyor means, and which may conveniently be constituted by the upper parts of an axially spaced pair of freely rotating wheels. A suitable paddle wheel may also be positioned intermediate the bumped section and the entering end of the roll-down belt to discharge lengths of conduit one at a time to the roll-down belt at spaced intervals.

To remove the danger that the pawl might tear the strip because of the back drag weight of a large strip roll, a looper is preferably provided to create and maintain a slack in the strip.

If desired, for example, to assure flatness of the label or to provide a given curvature for best cooperation with the selected shape, flat or otherwise, of the griddle surface, the contour of the label is controlled by a crimper operable in timed relationship with the looper.

There may also be special means to assure that the label is positioned as desired upon the griddle. To that end in the preferred embodiment of the apparatus, the griddle is surrounded on three sides by two sideboards and a back stop, such that when a tube reaches the griddle, it pushes the sideboards and back stop down to a flush position against suitable spring resistance, thereby leaving the label on an unrestricted table.

The griddle surface may be arranged to be angularly movable, e. g. by constituting the top piece of the griddle as a saddle which is mounted to rock on a support and which is thus freely alignable with the conduit lengths, to assure flat engagement between conduit lengths and labels, for example, in case a bowed length of conduit passes through the machine.

After the length of tubing and its label leave the griddle, they preferably pass, still under pressure applied by the roll-down belt, along a roll-down table, where the label application is completed. The top of the roll-down table, like the top of the griddle, may preferably be mounted to move angularly, as by including a saddle-like under-structure which rocks on a suitable support and which is thus freely alignable with bowed conduit or the like to assure flat engagement between each length of conduit and the roll-down table.

Accordingly, with certain important and novel features of our machine now preliminarily explained, it will be appreciated that an important

object of the invention is to provide a method and machine for applying adhesive labels from a perforated strip to lengths of conduit and the like, which will be of rapid, sure operation. For example, one specific embodiment of the machine outlined above and more particularly described below is being continuously operated at speed rates of 1000 to 5000 label applications an hour.

It is another object to provide improved, more effective and entirely reliable procedure and apparatus whereby successive labels in a strip of many, say 25,000 or any other desired number in a supply roll, are applied to successive lengths of tubing or like articles having a curved surface, each label being appropriately severed from the strip and adhered in smooth, conforming engagement with the surface of a tube. A particular object, in such method and machine, is to permit the use of labels carrying a heat-sensitive adhesive, so that each label is conveniently handled, heated and applied in a separate manner, without adverse effect of the label-heating or adhering operation on other parts of the apparatus or on repeated functioning with succeeding labels, and without interrupting the substantially continuous travel of successive lengths of tubing past the label-applying locality.

Additional, specific objects are to provide such a machine: in which there is no danger that a label will stick to the severing means or knife; in which labels will be fed to the label-applying locality, such as a heated griddle, only when a length of conduit approaches the griddle; and in which the lengths of conduit are fed to the griddle one at a time at spaced intervals.

It is a further object to provide such a machine which can be used with lengths of conduit of different diameters.

It is another object to provide such a machine in which the label feeding means operates positively and rapidly but cannot tear the label strip.

It is still a further object to provide apparatus of the character described which is adapted or adaptable to the application of labels at right angles or at any other desired angle relative to the axis of the conduit, a particular object being thus to provide means whereby the labels may be accurately positioned on the griddle or like surface in any preselected relationship to the lengths of conduit.

Other objects are to afford such apparatus: in which means is provided for controlling the contour of the labels, e. g. whether flat or bent in any desired way, as received on the griddle; in which the labels are applied at a uniform distance from the ends of the lengths of conduit; and in which bowed or otherwise slightly irregular lengths of conduit are provided for, should any such be fed to the machine.

It is a further object to provide such a machine in which most of the operating parts are below the conduit level as defined above, to render the operation of the machine very safe and to afford unusual convenience of structure and functioning, with full visibility of the actual labelling steps.

It is another object to provide such a machine which is relatively inexpensive to manufacture and yet is rugged and reliable and is cheap to operate.

The above and other objects and advantages will appear more clearly from the following description taken with the accompanying drawings in which:

Fig. 1 is a general plan view of one embodiment.

ment of the machine of the invention, herein illustrated and described by way of example, Fig. 1 also showing the transporting belts and other details;

Fig. 2 is an elevational view of the machine as seen from the discharge end thereof;

Fig. 3 is a sectional view taken on line 3—3 of Fig. 2;

Fig. 4 is likewise a vertical section, on line 4—4 of Fig. 2;

Fig. 5 is a plan view of the machine taken on line 5—5 of Fig. 4 below the roll-down belt;

Fig. 6 is a sectional view taken on line 6—6 of Fig. 2 and showing details of the gear box;

Fig. 7 is a sectional view taken on line 7—7 of Fig. 6 and showing further details of the gear box;

Fig. 8 is a view partly in vertical section showing details of the label-feeding mechanism with the pawl near its rearmost position and with no tube depressing the trigger;

Fig. 9 is a view similar to Fig. 8 but with the pawl at its intermediate position and just after a tube has depressed the trigger, so that the finger of the pawl has advanced a label part way onto the griddle;

Fig. 10 is a sectional view taken on line 10—10 of Fig. 8;

Fig. 11 is a sectional view taken on line 11—11 of Fig. 8;

Fig. 12 is a sectional view taken on line 12—12 of Fig. 8 and showing the saddle-like mounting of the griddle;

Fig. 13 is a perspective, exploded view of the griddle and the roll-down table and the mounting means for those parts, Fig. 13 also showing a label fully positioned on the griddle;

Fig. 14 is a plan view of a portion of a label strip of a type adapted to the disclosed embodiment of the invention;

Fig. 15 is a plan view of a portion of a modified form of label strip; and

Fig. 16 is a diagrammatic view of the pawl, knife and a label guide means shown in their relative positions just after a label has been severed, and also showing in dotted lines a portion of the label strip and a severed label.

Like reference characters denote like parts in the various views.

To get a general appreciation of our machine and the operation performed thereby, reference is first had to Fig. 1, wherein the labeler is shown in plain view, together with the tube transporting means. Tubes or lengths of conduit 14 are carried horizontally upon two parallel transporting belts 16 in the direction shown by the arrows thereon. For example, if the tubes 14 are each ten feet long, the belts 16 may conveniently be spaced about seven feet apart with the longitudinal centers of the tubes 14 half-way between the belts 16.

Before the tubes 14 reach the labeling machine, indicated generally at 18 and positioned adjacent one of the belts 16, the tubes are separated to assure that they are fed one at a time to the labeler at predetermined, spaced intervals. To effect this separation, the tubes first pass over a bumped section, which may preferably be a pair of freely-rotating, non-driven wheels 20 which are shown edgewise in Fig. 1 close to and between the belts 16 and which have upper segments projecting above the plane of the belts, as seen in Figs. 3 and 4. It will be appreciated that the tubes are pushed up on the bump constituted by the wheel segments, under the pres-

sure of the following line or array of tubes, side-wise abutting each other, on the belts. The wheels 20 discharge the tubes 14, one at a time, onto a pair of ramps 22, down which the separated tubes roll. Near the bottom of the ramps 22 is a continuously rotating paddle wheel 24 with its axis (represented by its shaft 26) parallel to the tubes. The paddle wheel 24 has a plurality of blades 28, five being illustrated (see for example Fig. 3 or Fig. 4), one of which picks up each advancing tube 14 and discharges it into the labeler 18. A runner 29 near one end of the tube is provided to guide the tube after it has been picked up by the paddle wheel 24.

In the labeler 18, the tube 14 is engaged by a continuously-moving, endless, roll-down belt 30, which rolls the tube along under pressure in the same direction as before. The labeling operation takes place while the tube 14 is engaged by the roll-down belt 30, and when the labeling operation is completed, the tube 14 leaves the roll-down belt 30 and returns to the transporting belts 16. It should be noted that from the time a tube 14 encounters the wheels 20 until the labeling action has been completed, that tube is at a level above the belts 16. A suitable support 33 having a portion corresponding to the runner 29 is provided to raise the end of the tube remote from the labeler 18 so that the tube will be substantially horizontal during the labeling operation. That is to say, the configuration of the upper, tube-supporting surface of the support 33 is approximately the same as the tube support parts for the end of the tubes corresponding to the labeler 18.

A side guide 32 is provided to aid in aligning the tubes 14 before they reach the labeler, so that the labeling operation will occur a uniform distance from the tube ends. A second guide for the other ends of the tubes may be provided if desired, but we have found this to be unnecessary in most cases, as an operator can easily push the incoming tubes against the guide 32.

Preferably, stops 31 are provided in the tube path between the ramps 22 and the paddle wheel 24, which stops are adjustable to assure that each blade 28 of the paddle wheel 24 picks up only one tube 14 at a time for any pre-selected tube diameter.

Next will be described in more detail the mechanism for feeding the tubes 14 through the labeler 18, particular reference at first being had to Figs. 3 and 4.

The runner 29 has a ramp 29r down which the tubes roll (one at a time) between the blades 28 of the paddle wheel 24 enroute to engagement by the roll-down belt 30. Intermediate the ramp 29r and the roll-down belt 30 the tubes encounter a pressure pad or lever 34 (see also Fig. 5) which is pivoted about an axis 36 that is parallel to the tubes 14. The lever 34 is biased upwardly by a spring 38, for reasons which will shortly appear. The tubes roll down the top surface of the lever 34, which is slightly inclined downward. Part way along the described surface, the tube first meets the roll-down belt 30 and is engaged thereby.

The roll-down belt 30 is looped around a driven pulley 40, i. e., driven by this belt) at its entering end and a driving pulley 42 at its discharge end and moves in the direction shown by the arrow at the top of Fig. 4.

The roll-down belt 30 exerts downward pressure against the tubes, and when a tube first comes in contact with the entering end of the

roll-down belt 30 (one tube is shown in that position in Fig. 4), such downward pressure squeezes the tube against the pressure lever 34, which is slightly lowered thereby by rotation about the axis 36. This rotation is against the upward bias of the spring 38, and the overall effect is to insure that the roll-down belt 30 will positively grab the tube.

After the roll-down belt 30 grabs the tube (i. e. to roll it along), but before the tube comes to the end of the lever 34, the tube becomes supported by the top, substantially horizontal surface of a timing lever 44 (Fig. 3) which is, like the pressure lever 34, pivoted at the axis 36. Also like the lever 34, the timing lever 44 is biased upwardly by a spring 46, so that when no tube is riding upon the lever 44, the horizontal top surface thereof will be separated from the roll-down belt 30 by a distance which is slightly less than the diameter of the tubes 14 to which labels are being applied.

Thus, when a tube passes along the lever 44, the downward pressure applied by the roll-down belt 30 is transmitted through the tube to depress the lever 44 against the upward bias of the spring 46. This depression has for its purpose to actuate a trigger mechanism to the end that a label will be positioned for adhesion to the tube. The trigger mechanism will be described below in detail in connection with the label-feeding mechanism.

The advancing tube then passes over or slightly above a stationary bar-shaped member 48, which cooperates with the knife as described below, and which is positioned with its horizontal upper surface separated from and below the roll-down belt 30 by a distance slightly more than the diameter of the tube. For convenience this member is identified as the bar 48. At the same time the tube is continuing to travel along the lever 44, which extends (in the direction of tube travel) past the lateral end of the bar 48, as seen in Fig. 5. Slightly after passing over the bar 48, the tube reaches the forward end of the timing lever 44, which is bevelled downwardly, as at 45 (Figs. 3 and 5) to ease the passage of the tube from the lever 44 onto a tube support 47 having its top substantially horizontal, and further having a notched portion 47a at its rearward end to make room for the forward end of the timing lever 44 and to provide a support for the lever when it is in its depressed position. The tube then (while its outer portion is over the tube support 47) passes onto a plate 50, which is heated as described below so as to constitute the griddle mentioned in the preliminary explanation hereinabove, and across which the tube is rolled under pressure applied from above by the roll-down belt 30. As will appear more clearly hereafter, a label will be positioned upon the griddle 50, adhesive side up, in advance of the arrival there of the tube, and the adhesive will be prepared to adhere the label to the tube. Thus, as the tube rolls across the griddle 50, it picks up the label, which adheres to the tube.

The top of the support 47 is slightly lower than the top of the griddle 50. The griddle 50 has a downwardly bevelled portion 51 (Fig. 4) at its forward edge to ease the tube onto the support 47.

The griddle 50 is surrounded on three sides, i. e. the back and the two sides, by a pair of sideboards 52 and a backstop 54 (Figs. 4, 5, 8, 9 and 12), all of which are mounted between two side plates 56 which are in turn mounted to

swing together about a horizontal axis defined by a rod 58 parallel to the tubes 14 (this pivotal connection to be described below). The plates 56 thus extend forwardly from the griddle 50, i. e. in the direction of motion of the tubes 14, past the axis 58. The outermost ends of the plates 56 are joined by a saddle piece 59a, by which they are pivotally connected as at 60 to a block 60a at the upper end of a vertical rod 62 which passes near its upper end through a hole in a bracket 63 carried by the roll-down table, described below. The lower end of the rod 62 carries a stop nut 66, and a coil spring 68 is held under compression between the nut 66 and the bracket 63 (see also Fig. 2). Thus, the spring 68 holds the sideboards 52 and the backstop 54 normally in a position in which the sideboards 52 and the backstop 54 protrude upwardly above the top of the griddle 50. In their rearward direction, i. e. toward the bar 48, the sideboards 52 extend slightly beyond the griddle 50.

The lower face of the piece 59a between the ends of the plates 56 is adapted to abut the upper faces of shelf portions 60b which project from the roll-down table (to be described), so as to limit the upward motion of the sideboards 52 and backstop 54, as shown.

The sideboards 52 have a thicker vertical dimension at their central portions than at their first-encountered (or rearward) ends so that their upper edges constitute sloping cam surfaces and hence as an advancing tube rolls toward and across the griddle 50, it will depress the sideboards 52 and the backstop 54, against the resistance of the spring 68. After the tube passes over the backstop 54, the spring 68 will be free once more to return the sideboards 52 and the backstop 54 to their normal up position. The sideboards 52 and the backstop 54 serve to locate the label in desired position on the griddle 50.

After passing the backstop 54, the tube is rolled, still under pressure applied from above by the roll-down belt 30, along a roll-down table 70, where such pressure completes the task of setting the label around the tube.

Between the griddle 50 and the roll-down table 70, the tube is supported upon the top of the tube support 47, which as aforesaid is slightly below the griddle and which is also slightly below the roll-down table.

Inasmuch as the tubes 14 may be slightly irregular, as by being bowed slightly (sometimes almost imperceptibly) in a lengthwise direction, and inasmuch as it is extremely desirable to have a perfectly flat contact between the tubes and the griddle 50 and the roll-down table 70, i. e. a full linear contact parallel to the axis of each tube, means are provided to assure that such will be the case.

To accomplish this self-aligning feature, the griddle 50 is made saddle-shaped in vertical, transverse section, as shown in Figs. 12 and 13. The inverted U-shaped portion 72a of the saddle rests upon the top of a base 72, as at 74. The top knife-like portion 74 of the base 72 extends in the direction of movement of the tubes 14 across the griddle 50.

The roll-down table 70 is similarly saddle-shaped in vertical, transverse section (see especially Fig. 13) and the inverted U-shaped portion 74a of the saddle rests upon the top 74 of the base 72 (Figs. 2, 4, and 13), which extends all the way from the rear or entering end of the griddle 50 to the forward or discharge end of the roll-down table 70; except for a cut-out portion 76 between

the griddle 50 and the roll-down table 70. The cut-out portion 76, registering with a similarly functioning space between the griddle 50 and the table 70, accommodates the backstop 54 and permits it to move downwardly when a tube 14 passes over the griddle 50. As shown in Figs. 2, 4 and 13, the roll-down table 70 is thus mounted on the base 72 in exactly the same way as the griddle 50, the latter being depicted in further detail in Fig. 12.

In this way the griddle 50 and the roll-down table 70 are each independently able to rock freely about an axis which extends along the path of the tubes 14, the upper edge of the upstanding base part 74 being rounded and the roof of the cavities 72a and 74a being rounded on a larger radius, as shown, to permit such motion while appropriately seating the griddle and table. For like accommodation of the rocking movement, which usually need not be very large, there is suitable space between the sides of the upstanding part 74 and the vertical walls of the cavities 72a and 74a, and likewise between the side faces of the griddle 50 and the sideboards 52 (Fig. 12).

The pivotal connection corresponding to the rod 58 for the sideboard plates 56, mentioned above, will now be described. As aforesaid, the rod 58 is between the griddle and the pivotal connection 60. The rod 58 passes through a hole 58b crosswise through the roll-down table 70, the hole 58b being of larger diameter than the rod 58. The rod 58 is located centrally in the hole 58b by bushings 58c. See Figs. 4 and 13. For clarity only the rod 58 is numbered in Fig. 4. The ends of the rod 58 also pass through holes in the plates 56, which are fixed to the rod. The rod 58 lies very loosely in a semi-circular recess 58d in the top 74 of the roll-down table base 72. By reason of this arrangement, the sideboard plates 56 rock freely back and forth with the roll-down table 70.

Two dowel pins 50a and 70a project upwardly from the top 74 of the base 72 and are loosely fitted in corresponding holes in the griddle 50 and the roll-down table 70, respectively, to prevent the griddle 50 and/or the table 70 to slide lengthwise relative to the base 72.

The net result of the griddle 50 and the roll-down table 70 being shaped and mounted as aforesaid is that flat contact between the tubes 14 and the griddle 50 and the roll-down table 70 is assured, even if the tubes 14 are slightly bowed lengthwise or for some other reason present their label-receiving portions at a small angle to the horizontal. Therefore, the pressure applied by the roll-down belt 30 (which is likewise slightly yieldable to the same effect) will press the labels squarely against the tubes to attain an effective seal.

The label feeding mechanism, which is entirely below the tubes 14, will be described next with particular reference to Figs. 4, 8, 9 and 11. The label feed is in the same direction as the tube movement. Labels 73, e. g. printed with the desired legend, are supplied in the form of a continuous paper strip 75 from a supply roll 76 (Fig. 3). The strip 75 may have suitable perforations between the individual labels to define the latter, for example laterally elongated perforations 78 located centrally of the strip 75 and of a length approximately half the width of the strip 75 (Figs. 11 and 14). The long dimension of each perforation 78 is perpendicular to the edges of the strip 75, there being (in the em-

bodiment of Figs. 11 and 14) one such perforation at each label-defining line across the strip. The strip 75 (of paper or other suitable label material) is provided on one side with heat-sensitive adhesive and is taken off the roll 76 with the adhesive side up. From the roll 76 the strip is passed over a freely rotating guide roller or spool 76a, under a looper 80 (to be described) and upwardly from the looper 80 onto a horizontal label guide 82. At the forward end of the guide 82, the strip 75 is passed or drawn between upper and lower label guides 84 and 86 respectively, which are inclined upwardly, for example at an angle of about 20° with the horizontal. It will be understood that the roll 76 is rotatably supported at a locality which in fact may be considerably further spaced from the looper 80 than appears in the somewhat diagrammatic representation of this part of Fig. 4.

The horizontal guide 82 has a cut-out portion 88 near the looper 80 which is designed to permit a crimper 90, or more accurately, a lower jaw 92 of the crimper 90, to be inserted therein. The crimper 90 also includes a stationary upper jaw 94 positioned above the lower jaw 92, which is vertically reciprocable into and out of engagement with the upper jaw 94. The label strip 75 is passed between the jaws 92 and 94 of the crimper 90 en route along the guide 82. The crimper 90 will be described in more detail hereafter.

The timing lever 44 (Figs. 3 and 5) carries a trigger block 96 on one side thereof in line with the label strip 75. The trigger block 96, which is thus depressible in response to the position of the lever 44, i. e. movable downward with the lever, is arranged so that there are two horizontally aligned studs 98 carried with it near its bottom. The trigger block 96 at its underside also has a guiding surface 100 positioned a short distance above the studs 98 and sloping upwardly along a path which generally extends from the under surface of the label guide 84 toward the similarly sloping, under guiding surface 110 of the stationary bar or block 48. That is to say, the sloping under surface 100 of the block 96 is adapted to constitute part of the roof of the path along which the label strip 75 is guided toward the griddle 50, it being understood that the surface 100 is normally elevated as shown in Fig. 8 but is depressed when a tube 14 rocks the lever 44 downwardly (Fig. 9), to a position closer to true alignment with the under surfaces of the guide 84 and the bar 48.

The label strip 75 is passed from the guides 84 and 86 between the surface 100 and the studs 98, which extend toward each other from either side of the label strip but have their inner ends spaced so as to leave a gap between them which corresponds in length substantially to the length of the perforations 78 in the strip 75. One of the studs 98 is mounted on a vertical plate 102a at the side of the lever 44 and the other stud 98 is mounted on a corresponding vertical plate 102 horizontally spaced from the plate 102a by the trigger block 96, the entire arrangement of the block 96, plates 102 and 102a and studs 98 thus being carried rigidly by the lever 44 and constituting a trigger assembly. The plate 102 is spaced sufficiently from the plate 102a to accommodate the label strip 75 between them, i. e. as it passes beneath the surface 100 and over the studs 98. At its forward end, i. e. furthest in the direction of label and tube travel, the block 96 has a vertical notch 100a, which is about as wide as the distance between the studs 98 (and thus

considerably narrower than the label strip) to permit free passage of a projecting end of the pawl described below and also to permit some visual inspection of the label advancing operation.

From the trigger block 96, the free end of the label strip 75 is drawn into sliding relationship beneath a bevelled portion 106 on the underside of the bar 48, and onward beneath the principal under surface 110 of the bar.

A pawl 104 is designed to reciprocate continuously lengthwise of and beneath the strip 75. The pawl 104 has a somewhat upwardly projecting finger 108 at one end, and the finger 108 is so shaped (e. g. as shown, with a horizontal notch or shoulder beneath it) as to be adapted to engage, given proper conditions, the perforations 78 separating the labels 73 of the strip 75. When an advancing tube 14 enters the roll-down belt 30 and depresses the timing lever 44 and consequently the trigger block 96 too, the surface 100 on the underside of the trigger block 96 pushes the label strip 75 downward so that the somewhat upstanding finger 108 of the reciprocating pawl 104 can enter and engage the perforation 78 between the last (i. e. leading) label 73 and the rest of the strip 75. This action occurs at or near that end of the path of stroke of the pawl 104 which is remote from the griddle 50, e. g. just as the pawl begins to advance from such locality of its path. The pawl 104 then moves toward the griddle 50, pushing the last label between the downwardly facing guiding surface 110 defined by the underside of the bar 48 and a further guiding surface afforded by a block 112 which is positioned just below the surface 110, and which may be conveniently carried (with suitable spacing structure) by the bar 48 at or near the end of the latter. At the same time the rest of the strip 75 is correspondingly pulled along the line in position for the next stroke of the pawl 104.

Preferably during this portion of the stroke of the pawl 104, the last label 73 is pushed part way, and advantageously somewhat more than half way onto the griddle 50 (Fig. 9). For example, if, as aforesaid, the label is $1\frac{1}{2}$ inches long, good results are attained if the label is pushed $\frac{7}{8}$ inch onto the griddle 50, the parts being designed to achieve such condition when the perforation at the trailing end of the label has just reached the further end of the bar 48. At this point, a divided cut-off knife 114 rises, straddles the finger 108 of the pawl 104 (which momentarily pauses), and severs the label (which is partially on the griddle 50) from the remainder of the strip 75 as by action against a cutting edge 116 formed at the lower corner or edge of the bar 48 which faces the griddle 50. The knife 114, as will be described below, reciprocates in timed relationship with the pawl 104. Thus during this phase of its stroke, the pawl 104 pushes the perforation 78 right up to the knife 114, so that the knife cuts the label along the line of the perforation.

As soon as the severing action is completed, the knife 114 recedes downward, and even before the knife 114 starts downward, the pawl 104 resumes its motion toward the griddle 50, passing through the central notch in the knife and pushing the now-severed label 73 the rest of the way up onto the griddle 50, to a position bounded by the sideboards 52 and the backstop 54. It will be noted that during the operation of the knife, the finger 108 overlies the forward (leading) edge of the perforation so as to retain its engagement with the severed label for the

further advance of the latter as just described. During this phase of the stroke, the pawl 104 itself passes between the surfaces 110 and 112, and the finger 108 of the pawl passes into a notch 118 provided therefor in the forward end of the griddle 50.

When the label severing operation occurs, the rearmost or trailing portion of the severed label 73 is beneath a wire label guide 120 (see especially Fig. 16) which holds the label down as the severing occurs, and which, while not always necessary, positively prevents the label 73 from popping up or bouncing in some undesired direction. Thus a more positive control is afforded over the course of the severed label 73 onto the griddle 50. The wires 120 are suitably fastened, as to the frame of the machine.

The griddle 50 is heated, as by an electric resistance heater 122 (Fig. 4) carried in the griddle 50, and having its lower end in a cavity 124 in the griddle base 12, to a temperature sufficient to prepare the adhesive material on the label almost instantaneously for adhesion to the tube 14. When the adhesive is thus prepared, the oncoming tube 14, being the one which caused the advance of the label 73 to the griddle 50, rolls over the griddle as explained above and picks up the label 73 via its adhesive (now sticky or tacky), whereupon adhesion is then completed as the tube and its label roll the length of the roll-down table 70.

A notch 118 in the rearward edge of the griddle 50 corresponds to the end of the stroke of the pawl, and as soon as the finger 108 of the pawl enters the notch 118 finally to position the label 73 on the griddle 50, the pawl 104 returns to the other end of its travel, ready to repeat the above-described work-stroke.

Above has been explained what happens when an advancing tube 14 passes over the timing lever 44 and depresses the trigger block 96. On the other hand, when no tube is approaching the griddle 50, it is desirable that no label be fed onto the griddle. Thus after a tube 14 has left the timing lever 44 at its end 45 (such action occurring just about as the tube is first passing onto the griddle 50, as shown in Fig. 5) the timing lever 44 returns to its normal up position (by the action of the spring 46), simultaneously raising the trigger block 96, including the surface 100 and the studs 98. When this occurs, and if no further tube 14 depresses the lever 44, the studs 98 will lift the label strip 75 upwardly, so that the finger 108 of the pawl can not engage the perforation 78 between the last label 73 and the remainder of the strip 75. That is to say, the pawl 104 nevertheless continues its reciprocal action, but the perforated part of the strip is held well above and clear of its path; the smooth-ended finger 108 is moved idly along beneath the strip 75 (indeed repeatedly back and forth until another tube 14 reaches the lever 44) and there is no advance of the strip at all.

Thus it is assured that one label 73 and no more will be fed onto the griddle for each tube 14; nor will any label be fed unless a tube is actually advancing to receive it.

Another important point to be noticed is that the described construction, i. e. with provision for advancing the labels no more than partially onto the griddle 50 before severing them from the strip, enables an air gap to be provided between the cut-off knife 114 and the griddle. This gap arrangement (clearly shown in Figs. 8 and 9) is significant, because it means that the knife

114 will be maintained cool enough during the operation of the machine so that it will not plasticize the heat-sensitive adhesive of the label. Thus the labels 73 cannot stick to the knife 114 and so be carried by it out of engagement with the pawl finger 108 or otherwise clog the machine.

As will now be apparent, the distance along the path of the label strip from the uppermost surfaces of the studs 98 to the end edge 116 of the bar 48 is approximately equal to the length of one label, so that after the knife has made a cut at the line of one perforation, the next succeeding perforation is in place to be lifted out of the path of the pawl unless another tube 14 is coming along.

It has been explained that the present apparatus is adapted for operation at relatively high speed, the illustrated machine being capable, for example, of providing from 1000 to at least 5000 label applications per hour. Where such is the case, it is practically necessary that the label strip 75 be very long. For example, the label supply roll 76 may start out containing as many as, say, 10,000 to 25,000 labels 73. The supply roll, particularly when large and heavy, produces a good deal of so-called back weight or drag against which the finger 108 of the pawl would have to pull in drawing the label strip 75 directly from the roll, with corresponding likelihood that the strip will be torn or mutilated, the inertia of the roll also enhancing any frictional drag that may occur along the path of the strip. Therefore, some means of relieving the back weight or pull should be provided. This is the function of the looper 80.

The looper 80 consists of a rubber-covered knob or wheel 128 mounted (i. e. fixed) with its axis horizontal on an arm 130 pivoted about a horizontal stub shaft 132 (see Figs. 3, 4 and 5). Specifically, the arm 130 carries an elongated hub 132a rotatably supported on the shaft 132, which is itself fixedly supported by a member 132b carried by or embodied with the main frame of the machine.

As aforesaid, the label strip 75 is passed from the supply roll 76, over the guide spool 76a and under the looper 80. More accurately, it is passed downwardly at, say, a 45° angle from the guide roller 76a around the underside of the wheel 128 and up to the horizontal guide 82. Means which will be described in detail below reciprocate the looper arm 130 about the axis 132 in timed relationship with the operation of the pawl 104, so that the motion of the looper knob 128 defines a small arc of a circle. When travelling downward along its path, the knob 128 pulls a length of label strip from the roll 76, to make up a slack label supply. This action occurs during the portion of the cycle in which the pawl 104 recedes from the griddle 50, i. e. while the pawl 104 is not working. As the pawl 104 again travels toward the griddle 50, the looper arm 130 is driven upwardly, to make sure that the previously withdrawn loop of label strip is truly slack (for the desired free advance of label strip by the pawl) and to position the looper, i. e. the knob 128, for repeating its operation to draw more label strip off of the supply roll 76 and re-establish the slack loop.

At least in most cases best labeling results are attained where it is made certain, by special provision (if necessary), that the ends of the labels 73 are fully heated on the griddle 50. While the present machine has been found re-

markably effective in achieving full, smooth adherence of all portions of each label to the passing tube, and thus in achieving adequate heating of the adhesive material throughout the label, it is sometimes possible to tolerate less than optimum temperature in the central portion of the label if the adhesive material at the ends is completely prepared and the label is there tightly adhered to the tubing. Furthermore, by making sure that when the label is first deposited on the griddle 50 both ends are in good heat-receiving contact with the heated surface, there is not only optimum adhesive preparation at the ends but also a tendency of all portions of the label ahead of a tube rolling upon it, to move toward rather than away from the griddle. The described initial disposition of the label can be attained either by forming the griddle 50 with a dip in the middle and using flat labels or by forming the griddle 50 flat and by contouring the labels 73 to have an upward bulge in their central portions, or indeed by having both a slight dip in the heated table and a slight bulge in the label. While any one of these provisions can be readily embodied in the illustrated machine, it is at present preferred to employ the second of them, using a plane griddle surface, inasmuch as the others necessitate lowering and raising the tubes 14 as they cross the griddle.

The upward bulge in the labels 73 is formed by the crimper 90, between the jaws 92 and 94 of which the strip 75 passes shortly after leaving the looper 80. As aforesaid, the upper jaw 94 is stationary, being mounted upon an arm 136 which may be conveniently secured to the same piece which forms the guide 82, and the lower jaw 92 reciprocates up and down toward and away from the upper jaw 94. The jaws 92 and 94 are shaped to provide the desired bulge, and are faced with thin rubber or like pads 93 and 95, respectively, which actually contact the strip 75, when the jaws 92 and 94 close.

The lower jaw 92 of the crimper 90 is driven from the looper 80 in timed relationship therewith by means of a spring-loaded friction clutch 134 pivotally mounted about the axis of the shaft 132, i. e. the looper axis. The clutch 134 includes a pincher mechanism consisting of a pincher arm 138 which has split upper and lower portions 138a and 138b, respectively, which are mounted upon the elongated hub 132a of the looper arm 130, the portions 138a, 138b being shaped to define, together, a cylindrical opening which conforms with the cylindrical outer surface of the hub 132a.

The split portions 138a are tightly held together around the hub 132a by a vertical stud or bolt 140 (on the side of the assembly nearest the crimper 90) which passes freely through a hole in the upper member 138a and is threaded into the lower member 138b, and by a compression spring 144 located in a vertical socket 146 in the upper portion 138a and bearing against the head of a vertical bolt or screw 142 which passes freely through the bottom of the socket and is threaded into the lower member 138b (on the side of the assembly remote from the crimper 90). Thus the described pincher arm assembly is clamped on the hub 132a of the looper arm 130 with a frictional grip that is determined by the compression of the spring 144, and that may, if desired, be changed by adjusting such compression.

The lower portion 138b of the pincher arm 138 has an essentially horizontal extension 138c (dis-

posed above and beside the path of the label strip on the guide table 82) from which there depends a bracket portion including a shelf 148 which juts out (toward the viewer in Fig. 4) into the gap 88 in the guide 82. It is on this shelf 148 that the lower, movable jaw 92 of the crimpler is mounted, immediately below the upper jaw 94.

The horizontal pincher arm extension 138c has a lower corner 150 which is adapted to abut the guide 82 at a suitable locality, i. e. removed from the label strip 75, to limit the downward displacement of the lower jaw 92 of the crimpler 90.

Thus, the parts 138a and 138b of the pincher arm 138 frictionally engage the elongated hub of the looper arm 130, and such engagement by friction, the amount of which can be varied by tightening or loosening the screw 142, causes the pincher arm 138 to follow the movement of the reciprocating looper arm 130. That is, when the looper arm 130 is driven downwardly, or in counterclockwise direction as seen in Fig. 4, the arm 138 will be frictionally driven upwardly, also in a counterclockwise direction as seen in Fig. 4, and the jaw 92 of the crimpler 90 will be moved upwardly against the jaw 94, to crimp a label 73.

Correspondingly, when the looper arm 130 is driven upwardly or clockwise, the pincher arm 138 will be frictionally driven downwardly or clockwise, to separate the jaw 92 from the jaw 94 until further movement is prevented by the corner 150 meeting the guide 82.

Preferably, the angular displacement of the looper arm 130 about the shaft 132 should be greater than the maximum annular displacement of the pincher arm 138 about the shaft 132, to assure tight crimping action. That is to say, with such an arrangement, when the looper arm 130 and the pincher arm 138 are moving counterclockwise, the jaw 92 should be stopped by the jaw 94 before the looper arm 130 reaches the end of its counterclockwise stroke. After jaws 92 and 94 are together and while the looper arm 130 is still moving counterclockwise, the friction can drive the jaw 92 no further, and slippage occurs between the looper hub 132a and the parts 138a, 138b. The same thing happens when the parts are moving in the other direction and the corner 150 encounters the guide 82.

From the above, it is apparent that the looper 80 creates a slack supply, or makes a loop, during the downward travel of the looper arm 130, and simultaneously, the crimpler 90 grabs the label strip 75 and crimps a label 73 to the desired contour, i. e. so that the labels will be heated most promptly at their ends while on the griddle 50. It will be understood that the crimpler jaws are located at a place remote from the label-severing end of the bar 48 by a distance equal to a whole number of label lengths, or rather, are located so that when the label strip is arrested during the return stroke of the pawl, the center of a label is always disposed at the central region of the jaws 92, 94. Thus it is assured that the desired contour will be applied squarely to each label. As will be appreciated, the jaws of the crimpler may have any configuration suitable to the crimping or bending action desired; for example in some cases (where it is simply desired to correct a slight curl in each label such as occasioned by snubbing around the wheel 25) the jaws may be simply plane, or where a slight, central, bulge (upward) is desired for the ultimately severed label, a wide inverted V-shape may be adapted for the jaw faces, as shown.

It will further be understood that the crimpler 75 at 196. The finger 108 of the pawl 104 is biased

90 should perform its crimping function while the pawl 104 is moving away from the griddle, i. e. toward the crimpler 90. Were it otherwise, the strip 75 would surely be torn, as the pawl 104 would be pulling the strip 75 while the crimpler 90 would be firmly holding the strip against movement.

For clarity of illustration and ease of understanding, the crimpler 90 is shown in Fig. 4 with its jaws 92 and 94 in their separated or open position, although it is to be understood that for the illustrated position of the looper arm 130 (i. e. at its furthest downward location), the jaws of the crimpler are actually closed.

15 The crimpler 90 performs the further function of preventing the label strip 75 from slipping back away from the pawl 104 while the pawl is receding from the griddle 50. In addition, of course, the crimpler positively holds the label strip at a locality beyond the looper, while the looper is drawing another length of strip from the supply roll; thus the strip-displacing movement of the knob 128 can only pull strip from the wheel and cannot pull any of it back from the path that extends past the trigger studs 98. It should be noted that in the machine shown, the actual displacement of the crimpler jaw 92 is advantageously very small, compared to the total swing of the looper knob 128; indeed the clamping of the jaws occurs essentially at the outset of the downward (counterclockwise) stroke of the looper, and complete opening of the jaws is effected at the beginning of the reverse (or slack-releasing) stroke of the looper.

35 To turn now to the driving and timing mechanism, reference is had particularly to Figs. 6 and 7, which show details of a gear box 152. A main shaft 154 is driven by sprockets 156 (in the direction shown by the arrow in Fig. 6) and chain belt means 157 from any suitable source of power, such as a Reeves transmission (not shown).

40 Mounted on the shaft 154 and rotatable therewith is a gear 158 which meshes with a gear 160 mounted on a second shaft 162. The shaft 162 also carries another gear 164 which meshes with a further gear 166 mounted on a third shaft 26 (Fig. 1), which is thus rotated through the above-described gear train to drive the paddle wheel 24 in continuous rotation.

50 An eccentric 168 is mounted on an end of the main shaft 154, outside the gear box 152. One end of an actuating rod 170 (Fig. 4) is connected to and is driven by the eccentric 168, by usual means, such as a stud 172, bearings and a bearing housing 174. The other end of the actuating rod 170 is pivotally connected to the looper arm 130 at 176 by a stud 178. Thus, the looper 80 (which in turn drives the crimpler 90) is continuously reciprocated by the eccentric 168.

60 Also mounted on the main shaft 154 is a pawl-actuating plate cam 180. A lever arm 182 is pivotally mounted at one end on and actuates another shaft 184. The other end of the arm 182 carries a cam follower 186 which is held in contact with the cam 180 by means of a counterbalancing spring 188 which constantly pushes a drill rod 190 against a platform 192 which juts out from the arm 182 adjacent the shaft 184 and on the opposite side thereof from the cam follower 186.

65 The shaft 184 has an end outside the gear box 152, and on that end is mounted the lower end of a pawl-actuating arm 194 (Figs. 3 and 4), the upper end of which is pivoted to the pawl 104 and on the opposite side thereof from the cam follower 186.

upwardly by a spring 198 stretched between the end of the pawl 104 remote from the finger 108 and a point part way down the arm 194.

The timing of the looper 80 and the pawl 104 (by means of the eccentric 163 and the cam 180, respectively) is such that when the pawl 104 is at the rear (non-pushing) end of its stroke, or preferably just as it starts its forward motion, the looper 80 is commencing its loop-freeing stroke (i. e. its upward motion), and the crimper 90 is simultaneously released.

Thus, the arm 194 moves in response to the cam 180 to drive the pawl 104 in the desired fashion, i. e. from its position furthest from the griddle 50 forward until the finger 108 has reached the knife 114, where the pawl hesitates, then up into the notch 118 in the griddle 50 and finally back once more to its original position, these movements of the pawl being dictated by the appropriate contour of the cam 180.

A knife-actuating face cam 200 is also mounted on the shaft 154. A cam follower 202 rides in the track of the cam 200 and is mounted on one end of a lever arm 204, the other end of which is pivotally mounted on and actuates a shaft 206. One end of the shaft 206 is outside the gear box 152 and rigidly mounted thereon is a knife arm 208. An extended portion of the knife arm 208 remote from the shaft 206 carries the knife 114, held in an undercut notch 208a by a clamping part 210 which constitutes one side of the notch (Fig. 7 showing these parts with the knife removed, for clarity). The cam 200 for the knife is so shaped as to actuate the knife arm 208 and the knife 114 just at the point where the finger 108 of the pawl has arrived beneath the stationary cutting edge 116 of the bar 48.

It will be understood from the above that the paddle wheel 24 is timed with the pawl 104 and the knife 114 to deliver tubes to the roll-down belt 30 at such a rate that no label will be fed to the griddle 50 while another tube is on the griddle, i. e. the tubes are sufficiently separated by the paddle wheel so that no tube will depress the lever 44 as another tube is undergoing a label application.

There remains to be described the assembly of the roll-down belt 30 and the means for driving and adjusting the same for tubes of varying diameters.

The driven pulley 40 is mounted on a horizontal shaft 212 (Fig. 4) suitably carried by a shaft holder 214 secured to the underside of a horizontal belt bracket 216. The driving pulley 42 is mounted on a horizontal shaft 218 (Figs. 3 and 4) suitably carried in bearings (not shown) in a bearing block 220 secured to the underside of the belt bracket 216. The shaft 218 also carries a sprocket 219.

The ends of the belt bracket 216 are pivotally connected to vertically disposed elevator shafts 222 and 224 as indicated at 226 in Fig. 2. Fig. 2 shows the pivotal connection between the bracket 216 and the shaft 222, corresponding to the driving pulley 42. The connection between the bracket 216 and the shaft 224 may be identical, or if necessary, the pivot hole can be elongated to accommodate vertical movement of the shaft 224 for reasons explained below.

The shafts 222 and 224 are carried within elevator housings 226 and 228, respectively, and are in slidable relationship therewith. The housings 226 and 228, which are stationary, are rig-

idly carried on the frame of the machine as shown at 230 and 231 in Fig. 3.

The driving pulley 42 is chain-driven from the shaft 162 (see also Figs. 6 and 7), which has a sprocket 232 mounted on one end. Pivotally mounted on the shaft 162 adjacent the sprocket 232 is one end of an arm 234, the other end of which is pivotally mounted on a floating shaft 236, which in turn carries a sprocket 238.

Also mounted on the floating shaft 236, to be turned with the sprocket 238, is a sprocket 240 which is preferably positioned vertically beneath the sprocket 219. The sprockets 219 and 240 are held a predetermined distance apart by sprocket spacers 242 and 244 which pivot respectively on the shafts 236 and 218 and which are bolted together in overlapping relationship.

Thus, to drive the driving pulley 42, the shaft 162 drives the sprocket 232, which drives the sprocket 238 by means of a chain 246. The sprocket 238 rotates the floating shaft 236, which in turn drives the sprocket 240. The latter sprocket drives the sprocket 219 by means of a chain 248, and the sprocket 219 drives the shaft 218 to turn the pulley 42. The pulley 42 drives the roll-down belt 30, which in turn frictionally drives the pulley 40.

The chain 248 may be equipped with a chain guard 250, if desired.

To accommodate tubes of different diameters, it is necessary that means be provided for bodily raising and lowering the roll-down belt 30 within predetermined limits.

Accordingly, the elevator shaft 222 is internally threaded at its lower end, and these threads are engaged by the threads of a screw 252. The screw 252 is rotatable by a crank 254 to raise or lower the shaft 222.

The elevator shaft 224 is provided with a similar screw-thread arrangement (not shown) at its lower end, for identically raising and lowering it.

A sprocket 256 rigidly carried on the shank of the screw 252 is also turned by the crank 254, and a chain 260 is driven thereby to turn a sprocket 258 which correspondingly turns a screw 252a in the bottom of the elevator shaft 224, the screw 252a being threaded to support the shaft 224.

Thus, when the crank 254 is operated, the shafts 222 and 224 are raised or lowered in unison, to raise or lower the pulleys 40 and 42 as desired.

When the crank 254 is turned to raise the roll-down belt 30, the sprocket 219 will likewise be raised. This will raise the assembly of the sprocket spacers 242 and 244 and the sprocket 240, the floating shaft 236 and the sprocket 238 as well, to rock the arm 234 in a counterclockwise direction (about the shaft 162) as seen in Fig. 3.

Sometimes an oversized tube might be fed into the machine. In such case, it is desirable that means be provided to cut off the machine automatically, to prevent injury thereto. Accordingly, the screw 252a (which rigidly carries the shaft 224) is not rigidly affixed to the sprocket 258 and its bearing assembly 259a, but instead, the screw 252a is keyed to the sprocket 258 but adapted to slide vertically therein and in the bearing assembly so that the screw 252a (and the shaft 224) can rise relative to their sprocket, which is fixed in vertical position. Held under compression between the sprocket 258 and a spring holder 300 rigidly mounted near the lower end of the shaft 224 is a spring 392.

The lower end of the shaft 224 is disposed to

control an electrical switch 354, shown for simplicity of illustration as having a pair of normally closed contacts 358, 360, which are arranged to control the driving motor 366 of the Reeves transmission mentioned above. It will be understood that conventional (more complex) circuit controlling instrumentalities are ordinarily used, but the simplified circuit shown in Fig. 3 sufficiently illustrates the function of the switch, namely that upon entry of an oversize conduit under the belt 30 the shaft 224 is forced upward (against the weight of the upper assembly and the force of spring 382) permitting the contacts 358, 360 to spring open and instantly deenergize the motor, so that the entire machine stops.

Thus, the described arrangement of parts permits the roll-down belt 30 to be raised or lowered by simply turning the crank 254.

To provide ample but yieldable downward pressure on the roll-down belt 30 between the pulleys 40 and 42 and hence to assure proper pressure against the tubes 14 as they are rolled over the griddle 50 and the roll-down table 70, a pressure foot 262 is positioned against the inner surface of the roll-down belt 30 at the location mentioned, in frictional engagement with the roll-down belt 30, e. g. as shown in Figs. 3 and 4.

A pressure foot support or framework 264 is secured to the underside of the belt bracket 216 by brackets 266 and 268. The framework 264 is shaped in vertical cross-section like an H lying on one side.

Studs 270 and 272 have their lower ends screwed into holes in the upper surface of the pressure foot 262 near opposite ends thereof, and are thus rigidly secured to the foot.

The studs 270 and 272 extend upwardly from the foot 262 and pass through holes 278 and 280, respectively, in the lower side of the framework 264, and through holes 282 and 284, respectively, in the upper side of the framework 264. The holes 278, 280, 282 and 284 are of larger diameter than the studs 270 and 272.

The studs 270 and 272 are provided at their upper ends with nuts 274 and 276, respectively, the lower surfaces of which rest upon the top surface of the upper side of the framework 264. Thus the framework 264 supports the foot 262 in suspended fashion, at an adjustable position, depending upon the setting of the nuts 274 and 276 upon their respective studs 270 and 272. It will be understood that the nuts 274 and 276 may be appropriately locked in the desired position of adjustment.

Intermediate the upper and lower sides of the framework 264, the studs 270 and 272 are provided with flanges or collars 286 and 288, respectively, spaced below the upper cross piece of the framework 264, each of flanges being suitably secured to its stud, e. g. being constituted by a washer supported on a suitably locked nut. Between these flanges and the upper cross piece the studs 270 and 272 are provided with springs 290 and 292, respectively, i. e. coil springs under compression, as shown.

The upper ends of the springs 290 and 292 bear against the lower surface of the upper side or piece of the framework 264 and their lower ends against the flanges 286 and 288, respectively, to bias the studs 270 and 272, and hence the pressure foot 262, resiliently downwardly against the roll-down belt 30.

The large holes 278, 280, 282, 284 in the framework 264 permit the foot 262, as supported by

the studs 270, 272, to rock appreciably for best conformity of the belt 30 with the tube or tubes passing beneath it. In the operation of the machine, the tubes sometimes, however, tend to carry the foot 262 so far forward that the stud 272 would bind in the hole 280 and interfere with the desired cushioning and rocking movement of the foot. Accordingly to prevent such difficulty a tie bar 294 (Fig. 4) may be inserted between the forward stud 272 and a rearward locality of the framework 264. The rear end of the bar 294 is tied to the lower side of the framework 264, as by a headed stud 359 and a nut, the head of the stud 359 serving to prevent the bar 294 from dropping off the stud. The forward end of the plate 294 (in the direction of belt travel) is provided with a hole through which the stud 272 passes in a loosely sliding fit as indicated at 295. The effect of this arrangement is to provide a tying but somewhat flexible connection extending from the framework 264, which is fixed in position, to keep the stud 272 from moving forwardly and thus to keep the stud 272 from binding in the hole 280.

As illustrated by way of example and as actually used, the apparatus will apply labels at right angles relative to the axis of the conduit, although by changing the line of the label feeding mechanism, the griddle 50 and the roll-down table 70, any other desired label application angle may be had.

Summary

By way of summary, the operation of our machine will be briefly recounted. After the machine is in operation, tubes are rolled, one at a time at spaced intervals, toward and across the heated griddle and then across the roll-down table, under downward pressure applied by the roll-down belt, which can be adjusted vertically to accommodate tubes of varying diameters.

En route to the griddle, the tube actuates the trigger mechanism to place the perforation between the last label of the strip and the remainder thereof in position where the finger of the continuously reciprocating pawl will engage said perforation and push said label part way onto the griddle (simultaneously pulling the remainder of the strip along to position the next perforation for subsequent engagement by the finger). When the pawl has pushed the label part way onto the griddle, its motion is momentarily halted, the cut-off knife rises, severs the label from the strip and recedes. Before the knife starts to recede, the pawl resumes its motion toward the griddle and pushes the severed label the rest of the way onto the griddle, where the adhesive of the label is prepared to stick the label to the tube as it rolls thereacross.

When no tube is advancing toward the griddle, the trigger mechanism positions the strip so that the finger of the pawl cannot engage it and hence no label will be fed onto the griddle.

We have experienced no difficulty from the fact that the tubes are positively driven (by the belt 30) only at or near one end while they are advancing through the machine.

Fig. 14 shows a portion of the label strip as actually used as described above. Fig. 15 shows a portion of a label strip 75a having another form of perforation, in which each successive pair of labels 73a is separated by two perforations 78a extending inwardly from the sides of the strip 75a at right angles relative to the centerline of the strip, and separated at the center. Although the type of label shown in Fig. 15 is useful,

especially if the machine is provided with a split pawl and a unitary knife, the single perforation type of label strip, for which we employ the arrangement of the single pawl and split knife as shown in other views herein, has been found to be satisfactory.

Many modifications and variations will be apparent or will occur to those skilled in the art, and it is not intended to limit the invention to the specific embodiment set forth by way of example, except as may be defined by the following claims.

We claim:

1. A machine for applying adhesive labels from a perforated strip to lengths of conduit and the like, comprising a table, means for advancing said lengths toward said table, means for rolling said lengths across said table under pressure one at a time at spaced intervals; means for positioning the foremost label of said strip on said table including a continuously operable, reciprocable pawl having a finger adapted to engage the perforation between said foremost label and the remainder of the strip to advance the strip; and a cut-off knife continuously reciprocable in timed relation with said pawl to sever said foremost label from the remainder of said strip when the foremost label is partially over said table, said pawl being thereafter effective to push said foremost label the rest of the way over and onto said table, means to sense the approach of one of said articles to said table, and means including said sensing means to actuate said label positioning means to place a label on the table before said one article reaches the table.

2. The invention set forth in claim 1, wherein the machine includes a crimper intermittently engaging the label strip for controlling the contour of the labels.

3. The invention set forth in claim 1, wherein said labels are coated with heat-sensitive adhesive material, means is provided for heating said table to plasticize the adhesive on said severed label, and said cut-off knife is separated from said table by an air gap to maintain the knife relatively cool and prevent adhesion of the labels thereto.

4. The invention set forth in claim 1, wherein the article sensing means includes a timing lever in the path of said advancing lengths, a spring biasing said lever upward, so that said advancing lengths will depress said lever against the bias of said spring, and said actuating means includes a stud positioned below and supporting said strip and following the motion of said lever, said stud being effective when and only when a length depresses said timing lever to position the perforation between said foremost label and the remainder of the strip in engageable relationship with the finger of said pawl.

5. The invention set forth in claim 1, wherein the machine further includes sideboards and a backstop surrounding said table, to position a label on said table accurately, and means biasing said sideboards and backstop upwardly, so that said sideboards and backstop will be depressed by said lengths as the latter roll across said table.

6. The invention set forth in claim 1, wherein a wire label guide to prevent disengagement of the severed label from the pawl finger is provided between said cut-off knife and said table.

7. The invention set forth in claim 1, wherein the table includes a rocking saddle-like mounting so that the table is freely alignable to assure flat

engagement between lengths of conduit and labels.

5 8. The invention set forth in claim 1, wherein the machine includes a first, pawl-actuating cam, a second, knife-actuating cam, a rotatable shaft on which said cams are rigidly mounted, and cam following means linking said first and second cams to said pawl and said knife, respectively, said cams being contoured to impart the reciprocating movement to said pawl and said knife.

10 9. A machine for applying adhesive labels from a perforated strip to lengths of conduit and the like, comprising a table, means for advancing said lengths toward said table, means for rolling said lengths across said table one at a time at spaced intervals, and means for positioning the foremost label on said table prior to the arrival there of each said length, including a continuously operable, reciprocable pawl having a finger adapted to engage the perforation between said foremost label and the remainder of the strip to advance the strip until said foremost label is partially over said table, to halt momentarily, and then to push said foremost label the rest of the way over and onto said table, a cut-off knife continuously reciprocable in timed relation with said pawl and adapted to sever said foremost label from the remainder of the strip while said pawl is halted momentarily, and means for positioning the perforation between said foremost label and the remainder of the strip in pawl-engaging position only when a length of conduit is advancing toward said table.

15 10. A machine for applying adhesive labels from a perforated strip to lengths of conduit and the like, comprising a table, means for advancing said lengths toward said table, means for rolling said lengths across said table one at a time at spaced intervals, and means for positioning the foremost label on said table prior to the arrival there of each said length, including a continuously operable, reciprocable pawl having a finger adapted to engage the perforation between said foremost label and the remainder of the strip to advance the strip until said foremost label is partially over said table, to halt momentarily, and then to push said foremost label the rest of the way over and onto said table, a cut-off knife continuously reciprocable in timed relation with said pawl and adapted to sever said foremost label from the remainder of the strip while said pawl is halted momentarily, and means for positioning the perforation between said foremost label and the remainder of the strip in pawl-engaging position only when a length of conduit is advancing toward said table.

20 11. A machine for applying adhesive labels from a perforated strip to lengths of conduit and the like, comprising a table, means for advancing said lengths toward said table, means for rolling said lengths across said table one at a time at spaced intervals, and means for positioning the foremost label on said table prior to the arrival there of each said length, including a continuously operable, reciprocable pawl having a finger adapted to engage the perforation between said foremost label and the remainder of the strip to advance the strip until said foremost label is partially over said table, to halt momentarily, and then to push said foremost label the rest of the way over and onto said table, a cut-off knife continuously reciprocable in timed relation with said pawl and adapted to sever said foremost label from the remainder of the strip while said pawl is halted momentarily, a timing lever in the path of said advancing lengths and operable thereby, and a trigger responsive in position to said lever, for positioning the perforation between said foremost label and the remainder of the strip in engageable relationship with the finger of said pawl only when a length of conduit operates said lever.

25 12. A machine for applying adhesive labels from a perforated strip to lengths of conduit and the like, comprising a table, means for rolling said lengths across said table one at a time at spaced intervals, means for positioning the foremost label on said table prior to the arrival there of each said length, including a continuously operable, reciprocable pawl having a finger adapted to engage the perforation between said foremost label and the remainder of the strip to advance the strip until said foremost label is partially over said table, to halt momentarily, and then to push said foremost label the rest of the way over and onto said table, a cut-off knife continuously reciprocable in timed relation with said pawl and adapted to sever said foremost label from the remainder of the strip while said pawl is halted momentarily, a timing lever in the path of said advancing lengths and operable thereby, and a trigger responsive in position to said lever, for positioning the perforation between said foremost label and the remainder of the strip in engageable relationship with the finger of said pawl only when a length of conduit operates said lever.

30 13. A machine for applying adhesive labels from a perforated strip to lengths of conduit and the like, comprising a table, means for rolling said lengths across said table one at a time at spaced intervals, means for positioning the foremost label on said table prior to the arrival there of each said length, including a continuously operable, reciprocable pawl having a finger adapted to engage the perforation between said foremost label and the remainder of the strip to advance the strip until said foremost label is partially over said table, to halt momentarily, and then to push said foremost label the rest of the way over and onto said table, a cut-off knife continuously reciprocable in timed relation with said pawl and adapted to sever said foremost label from the remainder of the strip while said pawl is halted momentarily, a timing lever in the path of said advancing lengths and operable thereby, and a trigger responsive in position to said lever, for positioning the perforation between said foremost label and the remainder of the strip in engageable relationship with the finger of said pawl only when a length of conduit operates said lever.

35 14. A machine for applying adhesive labels from a perforated strip to lengths of conduit and the like, comprising a table, means for rolling said lengths across said table one at a time at spaced intervals, means for positioning the foremost label on said table prior to the arrival there of each said length, including a continuously operable, reciprocable pawl having a finger adapted to engage the perforation between said foremost label and the remainder of the strip to advance the strip until said foremost label is partially over said table, to halt momentarily, and then to push said foremost label the rest of the way over and onto said table, a cut-off knife continuously reciprocable in timed relation with said pawl and adapted to sever said foremost label from the remainder of the strip while said pawl is halted momentarily, a timing lever in the path of said advancing lengths and operable thereby, and a trigger responsive in position to said lever, for positioning the perforation between said foremost label and the remainder of the strip in engageable relationship with the finger of said pawl only when a length of conduit operates said lever.

label from the remainder of the strip while said pawl is halted momentarily, a looper for building up and maintaining a slack in the strip, means for operating the looper during the non-work portion of the stroke of the pawl, and a crimper intermittently engaging the label strip at the initiation of each strip-drawing stroke of the looper for controlling the contour of the labels.

12. A machine for applying adhesive labels from a perforated strip to lengths of conduit and the like, comprising a griddle, a roll-down table, a transporting belt for advancing said lengths toward said griddle, a bumped section for separating said advancing lengths from each other, a roll-down belt for rolling said lengths across said griddle and then along said roll-down table under pressure, a continuously rotatable paddle wheel intermediate said bumped section and said roll-down belt for delivering said lengths to said roll-down belt one at a time at spaced intervals, and means for positioning the foremost label on said griddle prior to the arrival there of each said length, including a continuously operable, reciprocable pawl having a finger adapted to engage the perforation between said foremost label and the remainder of the strip to advance the strip and a cut-off knife continuously reciprocable in timed relation with said pawl to sever said foremost label from the remainder of said strip when the foremost label is more than half over said griddle, said pawl being thereafter effective to push said foremost label the rest of the way over and onto said griddle.

13. The invention set forth in claim 12, wherein in the machine further includes a pressure pad disposed in the path of lengths discharged by the paddle wheel, for resiliently urging each length against the roll-down belt, to assure that said roll-down belt will properly engage said lengths initially.

14. The invention set forth in claim 12, wherein in a pressure foot resiliently urges the roll-down belt downward, and means is provided for adjusting the amount of said resilience thus to adjust the pressure exerted upon said lengths by said roll-down belt.

15. The invention set forth in claim 12, wherein in the roll-down table includes a rocking saddle-like mounting so that the roll-down table is freely alignable to assure flat engagement with a labelled length of conduit rolling therealong under pressure.

16. The invention set forth in claim 12, wherein in a side guide for abutting the ends of the lengths as they are advanced by the transporting belt, is provided to assure that the labels will be applied a uniform distance from the ends of the lengths.

17. The invention set forth in claim 12, wherein in the machine includes a looper for building up and maintaining a slack in the label strip, and means for operating said looper during the non-work portion of the stroke of said pawl.

18. The invention set forth in claim 12, wherein in the top of said griddle is flat and a crimper intermittently engaging the label strip is provided to contour the labels to assure that the label ends will lie flat on said griddle.

19. The invention set forth in claim 12, wherein in the machine further includes a ramp intermediate said bumped section and said paddle wheel, and an adjustable stop at the bottom of said ramp to permit each spoke of said paddle wheel to pick up only one length at a time.

20. In a machine for applying labels to suc-

sive articles from a continuous strip of the labels, in combination, means providing a path for label strip into the machine past a shaping locality to an advancing locality, means at the advancing locality for engaging the strip and intermittently advancing the same a predetermined distance, and means at the shaping locality, including a pair of label-strip-engaging jaws and timed with said advancing means, for intermittently compressing the strip at times when said advancing means is inoperative to advance the strip, to impart a predetermined configuration to each label.

21. In a machine for applying labels to successive articles from a continuous strip of the labels, in combination, means providing a path for label strip into the machine past a shaping locality to an advancing locality, means at the advancing locality, including a reciprocating member, for intermittently engaging and advancing the strip a distance equal to the length of one label on the forward stroke of said member, said member on its rearward stroke returning past the label strip while the strip remains at rest in a predetermined position in the path, and means at the shaping locality including a pair of jaws disposed to engage a label at a predetermined position in the strip when the strip is at its aforesaid position of rest, for compressing the strip to impart a predetermined configuration to the engaged label, said compressing means being timed with the advancing means, to effect engagement of the aforesaid jaws with the strip only during the rearward stroke of the aforesaid reciprocating member.

22. In a machine for applying labels to successive articles from a continuous strip of the labels, in combination, means adapted to receive successive, leading labels of the strip, for applying them to successive articles, means for advancing successive articles along a predetermined path to said applying means, means providing a path for label strip to said applying means, means movable in said label strip path and engageable with the label strip, for periodically advancing the strip to advance successive labels to the applying means, and article-sensitive, label-strip-engageable means associated with both said paths and normally biased to hold the label strip out of its path to prevent its engagement by the strip-advancing means, but shiftable by an advancing article, for effecting displacement of the strip into its path to be engaged and advanced by the advancing means only when an article is being advanced to the applying means to receive a label.

23. In a machine for applying labels to successive cylindrical articles from a continuous strip of the labels, in combination, a table adapted to receive successive, leading labels of the strip, for applying them to successive articles, means for rolling successive articles along a predetermined path to and across said table, means providing a path for label strip to said table, means engageable with the label strip in said path, for periodically advancing the strip to dispose successive labels on the table, and article-sensitive lever means biased into a first position in said article path and shiftable to a second position by an article being rolled along said article path to the table, said lever means having label-strip-engageable means extending into the label-strip path for holding the strip out of engagement by the strip-advancing means when the lever means is in its first position and for effecting engagement of the strip by the strip-advancing means only when said lever means is in its second position.

24. In a machine for applying labels to successive cylindrical articles from a continuous strip of the labels, in combination, a table adapted to receive successive, leading labels of the strip, for applying them to successive articles, article-advancing means, including means for rolling successive articles across the table, means providing a path for label strip to said table, means for intermittently advancing the label strip, to dispose successive labels on the table, and means timed with said label-advancing means and including cutting means movable into said path, for severing the leading label of the strip in the course of its advance to the table.

25. In a machine for applying labels having a heat-sensitive adhesive to successive cylindrical articles from a continuous strip of the labels, in combination, a heated table adapted to receive successive, leading labels of the strip, for applying them to successive articles, article-advancing means, including means for rolling successive articles across the table, means providing a path for label strip to said table, means for intermittently advancing the label strip, to dispose successive labels on the table, and means timed with said label-advancing means and including cutting means movable into said path, for severing the leading label of the strip in the course of its advance to the table, said cutting means being separated from the table by an insulating region, to keep the cutting means sufficiently cool to prevent its adhering to a label.

26. In a machine for applying labels to successive cylindrical articles, in combination, article supporting means including a label-receiving table, over which successive articles may be rolled, article-advancing means including means for rolling successive articles under pressure across the table, means timed with the article-advancing means for advancing labels in succession to the table, to dispose a label thereon for application to each article rolled across the table, and guide means normally projecting adjacent the table to locate each advanced label in predetermined position thereon, said guide means being depressibly mounted, to move downward into non-projecting position as an article is rolled across the table.

27. In a machine for applying labels to successive, long cylindrical articles, in combination, means providing a supporting path over which the articles may be rolled through the machine, a table in said path to receive successive labels, means for advancing successive articles along said path, including means for rolling the articles in succession across the table, means for advancing labels in succession to the table, to dispose a label thereon for application to each article rolled across the table, and means mounting the table to rock freely crosswise of the path, for aligning the table with each article rolled across it.

28. In a machine for applying labels to successive articles from a continuous strip of the labels, in combination, a table adapted to receive successive labels, means for advancing successive articles across the table, for application of a label to each, means providing a path for label strip to said table, reciprocating means in said path, engageable with the label strip at the trailing edge of the foremost label of the strip, for advancing the label strip and disposing said foremost label on the table, and cutting means movable into said path at a distance from the table less than the length of one label and timed with said reciprocating means, for severing the fore-

most label from the strip when the leading edge of said foremost label is on the table.

29. In a machine for applying labels to successive cylindrical articles of predetermined diameter, in combination, means providing a supporting path over which the articles may be rolled through the machine, a table in said path, belt means over said path for rolling the articles along it, said belt means being adapted to roll the articles under pressure across the table, to effect application of the labels, means for disposing a label on said table for application to each article rolled across the table, and means for interrupting the operation of the machine should an article having a diameter in excess of said predetermined diameter be engaged by the belt means, said interrupting means being responsive to upward pressure against the belt means in excess of a predetermined amount.

30. A machine for severing labels coated with heat-sensitive adhesive material from a strip of such labels and applying the severed labels to cylindrical articles, comprising a flat table, means to heat said table, cutting means spaced from said table, means to advance the leading label of said strip, coated side up, past said cutting means toward said table, means to drive said cutting means and coordinated with said advancing means to cut the strip at the rearmost edge of the leading label before the portion of the label adjacent said rearmost edge is heated by contact with the table, said advancing means being thereafter effective to place the leading label on the table, means including said table defining a path for rolling movement of said articles, and means effective after each label is placed on the table to roll one of said cylindrical articles across the table so that its lateral surface rollingly contacts the adhesive side of the label thereon and the label adheres to the article.

31. Apparatus for feeding flexible sheet material, comprising means defining a path for edge-wise movement of said material, a pawl reciprocable along a path generally parallel to and adjacent said material path, said pawl having on its forward end a notch adapted to receive an edge of said sheet material, and a finger on the side of said notch nearest the material path and projecting into said material path, said finger having a contour smoothly continuous with the adjacent side of the notch, and means for reciprocating said pawl, said finger being effective during forward motion of said pawl to engage an edge of said material lying in said material path and guide said edge into said notch, said pawl being effective during its further forward motion to push said sheet material along its path.

32. Apparatus for feeding flexible sheet material as defined in claim 31, in which said pawl is reciprocated continuously and is narrower than said sheet material, and including means operable to prevent feeding of said material during forward movement of said pawl, said feeding preventing means comprising an element on the same side of said sheet material as said pawl and movable into said material path to engage said material and deflect it from its path in a direction away from the path of the pawl, so that during a subsequent forward movement of the pawl, the finger is ineffective to engage an edge of said material.

33. Apparatus for feeding strip material in the form of sections separated by perforations extending less than the full width of the strip, comprising means defining a path for endwise

movement of said strip material, a pawl narrower than said separating perforations and reciprocable along a path generally parallel to and adjacent said material path, said pawl having on its forward end a notch adapted to receive an edge of said strip material defining one of said perforations, and a finger on the side of the notch nearest the material path and projecting into said path, said finger having a contour smoothly continuous with the adjacent side of the notch, means for reciprocating said pawl, said finger being effective during forward motion of the pawl to enter one of said perforations and guide said edge into said notch, said pawl being effective during its further forward motion to feed said strip material along its path, and means operable to prevent feeding of said material during forward movement of said pawl, said feeding preventing means comprising an element on the same side of said sheet material as said pawl and adjacent the rearmost pawl position, said element being movable into said material path to engage said material and deflect it from its path in a direction away from the path of the pawl, so that during a subsequent forward movement of the pawl, the finger is ineffective to engage a perforation in said strip material.

34. Apparatus for feeding strip material in the form of sections separated by perforations extending less than the full width of the strip, comprising means defining a path for endwise movement of said strip material, a pawl narrower than said separating perforations and reciprocable along a path generally parallel to and adjacent said material path, said pawl having on its forward end a notch adapted to receive an edge of said strip material defining one of said perforations, and a finger on the side of the notch nearest the material path and projecting into said path, said finger having a contour smoothly continuous with the adjacent side of the notch, means for reciprocating said pawl, said finger being effective during forward motion of the pawl to enter one of said perforations and guide said edge into said notch, said pawl being effective during its further forward motion to feed said strip material along its path, a cutter reciprocable in a direction generally perpendicular to the plane of said strip material, said cutter being located adjacent said pawl and spanning that portion of the strip material width not occupied by said perforations, and means for reciprocating said cutter to engage said strip and separate said sections.

35. Apparatus for feeding and cutting strip material as defined in claim 34, comprising common driving means connected to said pawl reciprocating means and said cutter reciprocating means and cooperating therewith to move said pawl forwardly until the line separating two of said sections is aligned with said cutter, then to reciprocate said cutter to sever the leading section from the strip and then to move the pawl

forwardly again to push the severed section away from the strip.

36. Apparatus for feeding and cutting strip material as defined in claim 35, comprising a fixed cutter guide on the opposite side of the strip from the cutter and cooperating with the cutter to shear the material, and a material guide on the same side of the strip as the cutter guide and spaced forwardly therefrom along the material path by a distance slightly greater than the cutter thickness, so that the cutter moves between the cutter guide and the material guide, said material guide serving to prevent deflection of the severed section from said path by the cutter.
37. In a machine for applying labels to successive cylindrical articles of predetermined diameter, in combination, means providing a supporting path over which the articles may be rolled through the machine, a table in said path, belt means over said path for rolling the articles along it, said belt means being adapted to roll the articles under pressure across the table, to effect application of the labels, means for disposing a label on said table for application to each article rolled across the table, yieldable means for applying pressure to the upper side of said belt means, said yieldable means including a pressure foot adapted to engage the upper surface of said belt means, a fixed frame above said pressure foot, a plurality of studs fixed in said foot and projecting upwardly therefrom, said frame having apertures therein to receive said studs, said apertures having diameters greater than said studs so that the studs are freely movable vertically therethrough, spring means retained between said frame and said studs and biasing said pressure foot against said belt, a pin fixed to said frame and projecting vertically downward therefrom, a horizontal tie-bar apertured at one end to receive said pin slidably and apertured at the other end to receive one of said studs loosely, said aperture at the other end having a diameter smaller than that of said frame apertures, said tie-bar being freely slidable vertically on said pin and said one stud, said tie-bar being effective to limit horizontal movement of the pressure foot to a distance less than said frame aperture diameter and thereby to prevent binding engagement of the studs with the sides of said frame apertures.
